BOX

Joseph R. Watkins, Dover, N. J., assignor to Foster Grant Co., Inc., Leominster, Mass., a corporation of Massachusetts

Application October 24, 1951, Serial No. 17,089

Term of patent 14 years

(Cl. D58—12.6)

To all whom it may concern:

Be it known that I, Joseph R. Watkins, a citizen of the United States, residing at Dover, Morris county, and State of New Jersey, have invented a new, original, and ornamental Design for a Box, of which the following is a specification, reference being had to the accompanying drawings, forming part thereof, in which:

Fig. 1 is a perspective view of a box with the lid partly open, showing my new design;

Fig. 2 is an end view of the box, showing the lid closed;

Fig. 3 is a top plan view thereof; and,

Fig. 4 is a front view.

I claim:

The ornamental design for a box, substantially as shown.

JOSEPH R. WATKINS.
